UNITED STATES PATENT OFFICE.

HERSCHEL CATON, OF KANSAS CITY, AND EUGENE CATON, OF ROSEDALE, KANSAS, AND LLOYD C. HOWARD, OF KANSAS CITY, MISSOURI, ASSIGNEES TO CATON PRINTING COMPANY, OF KANSAS CITY, MISSOURI, A CORPORATION OF MISSOURI.

METHOD OF SLIP-SHEETING AND MEANS FOR PRACTICING THE SAME.

Application filed October 21, 1927. Serial No. 227,707.

Our invention relates to printing presses and more particularly to devices for conducting paper into and through presses.

In the printing art, the ink on a printed sheet may offset on the back of the following sheet, and when offsetting is serious, slip sheets are interposed between printed sheets and succeeding sheets to receive possible offset and protect the printed sheets. The slip sheet paper is usually of a special character adapted to prevent smearing; and ordinarily must be placed by hand upon each printed sheet as it comes from the press. The offset problem is more pronounced in connection with the use of roll-feed printing machines including rotary sheet printing presses that cut sheets from the roll of print paper before printing, where it is impracticable to insert slip sheets manually because of the speed of delivery. For example, in one class of roll-feed printing machines running at high speed, a plurality of printed sheets may be assembled on a cylinder by the machine immediately upon coming from the impression cylinder or other cylinder, and delivered in lots to a shelf; sufficient time is available for depositing slip sheets manually between the said lots of printed sheets, but no facility has seemed available for installing slip sheets between the members composing said lots prior to assembly on the cylinder.

Further problems are involved when the print paper is particularly fragile, or difficult to handle because of other unusual characteristics, or because of ink or color printing factor.

Offsetting is particularly serious when the paper printed is transparent or translucent, and offset marks may show through the face of the sheet where not obstructed by the printing, or may confuse or mar the effect of printing.

The principal object of our invention, therefore, is to associate slip sheets with freshly printed sheets printed on a roll-feed press. A further object of the invention is to introduce an auxiliary strip into association with print paper in a printing apparatus, for supporting the print paper or for preventing offset, and to deliver auxiliary sheets synchronously with printed sheets.

A further and particular object of the invention is to introduce an auxiliary web into a machine performing a plurality of opera-

tions including severance on a principal web, 55 and provide for conducting the auxiliary web and sheets cut therefrom in association with said principal web and sheets cut therefrom and for delivering the auxiliary web sheets in company with the principal web sheets. 60

In accomplishing these and other objects of the invention we have provided a new and novel method, and improved details of structure for using the method, the preferred forms of which are illustrated in the accompanying drawings, wherein:

Fig. 1 is a perspective view of a portion of a roll-feed printing press showing the means of feeding print paper thereto, severing the sheets, and delivering them from the press, 70 with which our slip-sheet feeding device is combined, and whereby our method of slip-sheeting is illustrated.

Fig. 2 is an elevation of the machine, illustrating the method from a different point of view. 75

Fig. 3 is a detail perspective view of the slip sheet roll-supporting element of our preferred structure for employing the method, 80 the members partly disassembled.

Referring more in detail to the drawings:

1 designates generally a printing press comprising vertical frame members 2 and 3 upon which are journaled a printing plate cylinder 4, an impression cylinder 5 and a roll-supporting bracket element 6 in which a web roller shaft 7 is journaled. The web 8 is fed to the machine over a tension roller 9 supported on a bracket 10, an idler 11 journaled in the frame, and feed rollers 12; the feed rollers delivering the web to a cutting shelf 13 where a blade 14 on a cutting cylinder 15 severs the web, the sheets proceeding over endless tape 16 supported in tension by a plurality of rollers 17 and being retained by tape 18 supported on rollers 19 to the impression cylinder 5, which grasps each sheet with grippers such as 20, carries it into contact with the printing plate cylinder 4, and releases the sheet at a suitable position for 100 grasping of the sheet by the grippers 21 of a delivery cylinder 22.

The delivery cylinder ordinarily is adapted to receive a plurality of sheets, for example five sheets, from the impression cylinder 105 in succession, and release and deliver the five sheets in a single lot to an inclined jogger element generally designated 23 and including

fly sticks 24, selected ones of which are provided with shelf or stop members 25 to receive the delivered sheets, the fly sticks fixed to a shaft 26 journaled in the frame for rocking the fly sticks.

- 5 A rack hub 27 is provided on the shaft and a rack segment 28, actuated under normal operation of a machine of this character, rotates the shaft and rocks the fly sticks 24.
- 10 The fly sticks, rocking, deliver the plurality of sheets that are assembled on the stop members to a gathering table 29, returning after delivery to position for receiving another lot of sheets from the delivery cylinder. The 15 actuation of the machine is controlled through the operating lever 30.

The printing, web-feeding, cutting and delivering structures have been thus described since they provide means for carrying out 20 our new method, and elements with which our new structure is combined, the web and printed sheets being handled for my purpose as in ordinary practice.

Our invention consists in the introduction 25 of a slip sheet into the means for carrying the print paper into and through the machine for delivery by the mechanism that normally delivers the printed sheets, and comprises preferably, as in the illustrated application 30 of the invention, the provision of an auxiliary or supplemental web 31 of slip sheet paper, supporting paper, or other backing strip, supplied on a roll 32 supported on a rotatable shaft 33 by journal block members 34 and 35 fixed 35 on extension members 36 secured to the printing press frame. The roll-supporting members may be of a conventional type and preferably include a disk 37 fixed to the shaft 33 and rotatably positioned in a journal member 38 comprising hinged recessed halves 40 clamped together for braking the rotatable shaft as desired by a set screw 39, and means 45 for supporting the journal member 38 adjacent the block 34, and shifting the shaft, and roll carried thereby, transversely of the 50 press to adjust the slip sheet web to the web of print paper. Said supporting and shifting means include retaining arms 40 fixed to the journal member halves projecting 55 across the edges of the journal recess, to retain the disk, and a threaded gauge pin 41 extending through the journal element 34 rotatably, restrained from longitudinal movement therethrough by means generally indicated by a block 42, the inner end of the 60 pin being threadedly engaged in an opening 43 of the journal block 34.

Paired brackets 44 are pivoted downwardly 65 on the extension members 36 adjacent the ends thereof and a tension roller 45 is rotatably carried in the ends of the brackets in bearing members 46 adjustable lengthwise of the brackets by spring elements 47 for spacing the roller from the extension support, and the 70 web of the slip sheet passes over this roller.

A slip sheet guide roller 48 is rotatably supported on a bracket 49 by the frame of the press in alignment with the guide rollers and idlers of the web to be printed. The continuous web of the slip sheet element may be carried over the tension roller and the guide roller and brought into relation with the web to be printed, assembled therewith over the idler 11 and fed into the feed rollers 12 for carriage through the printing press coincidentally with the web to be printed. 75

In practicing our invention a printing press of the roll-feed variety provided with a web to be printed is assumed and the slip sheet roll supporting means provided. When the 80 printing is to be done the end of the slip sheet is drawn from the roll over the tension and idler rollers into association with the web to be printed, and the two together are carried over the idler and into the feed rollers. 85 The press is started and the feed rollers deliver the two continuous strips of paper to the cutting platform and to the guide tapes that draw and conduct the paper towards the impression cylinder. The cutting cylinder 90 operates to cut the web as usual and at the same time cuts the slip sheet web so that a slip sheet of the same length as the sheet to be printed is carried with and beneath the sheet to be printed to the impression cylinder, the two are gripped by the grippers of 95 said cylinder and carried thereby to the printing plate where the plate impresses the ink upon the sheet to be printed; the slip sheet constituting a backing therefor. The impression cylinder carries the two sheets together to the delivery cylinder, the grippers of which grasp them; the delivery cylinder collecting a plurality of pairs consisting of 100 printed sheet and slip sheet and delivering 105 the lot to the jogger. Each of the printed sheets has upon its back therefore, a slip sheet which protects its back from ink on the face of an adjacent printed sheet. When five of the pairs comprising a printed sheet and a 110 slip sheet have been delivered to the jogger, the fly sticks operate to deliver the assembly to the gathering table. 115

While we have illustrated a roll-supporting bracket and rollers for delivering the slip sheet web to the means carrying the print web for conduct thereof by said carrying means through the machine, the particular means of accomplishing the result may be varied without departure from the spirit of our invention, and the steps may be varied or reduced or their order changed for application to a particular situation, for example, by providing for the cutting of the web after the print paper has been printed. 120

What we claim and desire to secure by Letters Patent is:

1. In combination with a roll-feed printing press, means for conducting the web of the print roll to the press, means for severing 125

- sheets from the print web, and means for delivering the severed and printed sheets, a slip-sheet handling device comprising a support for a roll of slip-sheet paper, and means for delivering the web of said slip-sheet roll to said print web conducting means for severance of sheets from the slip-sheet web by print sheet severing means and carriage of slip sheets through the press and delivery therefrom with said print web sheets by said print web sheet delivering means. 6
2. In combination with a roll-feed printing press having means for cutting sheets from a print paper strip for printing, and means for delivering the printed sheets, a slip-sheet handling device comprising means for delivering a slip sheet strip to said print paper cutting means for severance of slip sheets thereby for carriage by said printed sheet delivering means simultaneously with the printed sheets. 15
3. In combination with means for feeding a print strip to a printing machine and means for dividing the print strip into sheets, means for delivering an auxiliary strip in slip-sheet relation with the print strip for division into sheets by said print strip-dividing means, and means for conducting said print and slip sheets through the printing machine simultaneously and in superimposed relation. 25
4. In the art of printing a strip, the method of slip-sheeting consisting of advancing a strip of slip-sheeting synchronously with the strip to be printed, cutting the strips simultaneously, and delivering the cut sheets together. 30
5. In the printing art, the method of slip-sheeting comprising introducing a slip-sheet strip into the paper-carrying members of a printing press in company with the paper to
- be printed, cutting the strip into sheets, carrying the slip sheets through the press with the print paper, and delivering the slip sheets with the printed paper. 40
6. In the art of printing, the method of slip-sheeting the sheets printed by a roll-feed press comprising the feeding of a slip-sheet strip to the press, the severing of separate sheets from the strip by the press, the carriage of slip sheets by print sheet carrying means, and the delivery of a slip sheet in company with each printed sheet. 45
7. In the art of roll-feed printing, the method of slip-sheeting comprising introducing a slip-sheet web into the print paper carrying members, severing sheets from the web, carrying the slip sheets through the press with the print paper, and delivering a slip-sheet with each printed sheet. 50
8. In the art of roll-feed printing, the method of slip-sheeting including provision of a roll of slip-sheet paper, carrying the slip-sheet web to the press with the print paper, dividing the slip-sheet web into sheets, and delivering slip-sheets coincidently with the printed sheets. 55
9. In the printing art, the method of supporting print paper including introducing an auxiliary strip into the paper-carrying members of a printing press in company with the paper to be printed, cutting the strip into sheets, carrying the auxiliary sheets with the print paper, and delivering the auxiliary sheets with the printed paper. 60

DISCLAIMER

1,693,886.—*Herschel Caton, Kansas City, Eugene Caton, Rosedale, Kans., and Lloyd C. Howard, Kansas City, Mo.* METHOD OF SLIP-SHEETING AND MEANS FOR PRACTICING THE SAME. Patent dated December 4, 1928. Disclaimer filed May 13, 1933, by the assignee, *Caton Printing Company*.

Hereby enters the following disclaimer in relation to said patent: Petitioner disclaims from the scope of the specification of the said patent, the slip-sheeting of all print sheets excepting those that are difficult to handle because of the unusual characteristics of transparency and a tendency to curl when unrestrained, and particularly print sheets exemplified by the commercial article known as "Cellophane" and the like, the handling of which, through automatic printing presses, was, prior to the present invention, regarded as impracticable; and from the scope of each and all of the claims of said Letters Patent, any method or means of practicing the method defined in said claims, except such as employed in the printing of transparent material difficult to handle and having a tendency to curl if unrestrained.

[Official Gazette June 18, 1933.]

- sheets from the print web, and means for delivering the severed and printed sheets, a slip-sheet handling device comprising a support for a roll of slip-sheet paper, and means for delivering the web of said slip-sheet roll to said print web conducting means for severance of sheets from the slip-sheet web by print sheet severing means and carriage of slip sheets through the press and delivery therefrom with said print web sheets by said print web sheet delivering means. 6
2. In combination with a roll-feed printing press having means for cutting sheets from a print paper strip for printing, and means for delivering the printed sheets, a slip-sheet handling device comprising means for delivering a slip sheet strip to said print paper cutting means for severance of slip sheets thereby for carriage by said printed sheet delivering means simultaneously with the printed sheets. 15
3. In combination with means for feeding a print strip to a printing machine and means for dividing the print strip into sheets, means for delivering an auxiliary strip in slip-sheet relation with the print strip for division into sheets by said print strip-dividing means, and means for conducting said print and slip sheets through the printing machine simultaneously and in superimposed relation. 25
4. In the art of printing a strip, the method of slip-sheeting consisting of advancing a strip of slip-sheeting synchronously with the strip to be printed, cutting the strips simultaneously, and delivering the cut sheets together. 30
5. In the printing art, the method of slip-sheeting comprising introducing a slip-sheet strip into the paper-carrying members of a printing press in company with the paper to
- be printed, cutting the strip into sheets, carrying the slip sheets through the press with the print paper, and delivering the slip sheets with the printed paper. 40
6. In the art of printing, the method of slip-sheeting the sheets printed by a roll-feed press comprising the feeding of a slip-sheet strip to the press, the severing of separate sheets from the strip by the press, the carriage of slip sheets by print sheet carrying means, and the delivery of a slip sheet in company with each printed sheet. 45
7. In the art of roll-feed printing, the method of slip-sheeting comprising introducing a slip-sheet web into the print paper carrying members, severing sheets from the web, carrying the slip sheets through the press with the print paper, and delivering a slip sheet with each printed sheet. 50
8. In the art of roll-feed printing, the method of slip-sheeting including provision of a roll of slip-sheet paper, carrying the slip-sheet web to the press with the print paper, dividing the slip-sheet web into sheets, and delivering slip-sheets coincidently with the printed sheets. 55
9. In the printing art, the method of supporting print paper including introducing an auxiliary strip into the paper-carrying members of a printing press in company with the paper to be printed, cutting the strip into sheets, carrying the auxiliary sheets with the print paper, and delivering the auxiliary sheets with the printed paper. 60
